J. B. HOLDEN

TYPEWRITING MACHINE

Filed Sept. 8, 1923

UNITED STATES PATENT OFFICE.

JOSEPH B. HOLDEN, OF SYRACUSE, NEW YORK, ASSIGNOR TO REMINGTON TYPE-WRITER COMPANY, OF ILLION, NEW YORK, A CORPORATION OF NEW YORK.

TYPEWRITING MACHINE.

Application filed September 8, 1923. Serial No. 661,619.

To all whom it may concern:

Be it known that I, JOSEPH B. HOLDEN, a citizen of the United States, and resident of Syracuse, in the county of Onondaga and 5 State of New York, have invented certain new and useful Improvements in Typewriting Machines, of which the following is a specification.

My invention relates to platen adjusting 10 devices for typewriting machines, and its object is to provide new and improved means whereby the platen may be adjusted on its frame or support so as to bring the printing face in proper position normally to receive the type impressions.

To the above and other ends which will hereinafter appear, my invention consists in the features of construction, combinations of devices and arrangements of parts herein- 20 after described and particularly pointed out in the claims.

I have shown my invention as applied to the platen and carriage of a front strike typewriting machine, the carriage and 25 platen of the Smith Premier No. 60 machine being herein illustrated, but the nature of the invention is such that it may be readily adapted to other styles of typewriting machines. In carrying out the invention I provide simple and effective means for raising 30 or lowering one part of the platen carrier or carriage relatively to another part to change their normal set relationship thus raising or lowering to a corresponding extent and resetting the printing face of the platen; and I also provide means co-operative 35 with the axle of the platen to adjust the platen on its support in a fore-and-aft direction so as to adjust the printing face substantially horizontally for the purpose 40 more especially of bringing it into proper co-operative relationship with the anvil or striking abutment of the type bars. My invention will be described in detail in connection 45 with the accompanying drawing, wherein

Figure 1 is a fragmentary end view of the carriage and its bearing as viewed from the left-hand side, parts being sectioned away 50 for the sake of clearness and one of the type bars being shown in printing position.

Figure 2 is a view corresponding to Fig. 1 but taken from the right-hand side, showing the right-hand end of the platen and 55 carriage in elevation.

Figure 3 is a fragmentary front view partly in section of the platen and associate parts.

Figure 4 is an enlarged fragmentary end view partly in section showing some of the 60 parts of Fig. 1 after readjustment.

Figure 5 is a fragmentary horizontal sectional view taken on the plane indicated by the section line 1—1 in Fig. 1 and looking downward.

Rising from the top plate 1 of the machine are a pair of stationary brackets, 2 spaced apart, one disposed at each side of the machine, and each bracket being rearwardly curved or goose-necked. These brackets are 70 only fragmentarily shown in the drawing but are like the brackets shown in the Smith Premier #60 machine and in the application of E. E. Barney #650,683 filed July 20, 1923. Secured to the upper end portions of the brackets 2 by screws 3 is a stationary guide rail 4, the lower portions of the brackets having secured to them by screws 5 a guide rail 6. The two 80 guide rails 4 and 6 are parallel and formed with oppositely faced V-shaped grooves which receive antifriction rollers 7, said rollers likewise co-operating with V grooves formed in the top and bottom of a race rail or slide bar 8 that serves as the 85 rear bar of a traveling platen carriage. Said carriage further comprises end bars 9 extending forward from the ends of the bar 8 and adjustably secured thereto in a new manner hereinafter to be described. The 90 carriage comprising the end bars 9 and rear bar 8 rotatably supports a cylindrical platen 10 provided at one end with a line space ratchet wheel 11 and having axle portions 12 which project from the ends of the platen 95 and are adjustably supported on the end bars 9 in a novel manner presently to be described. The projecting ends of the axle portions 12 receive the usual finger wheels 13 having hubs 14 which are secured by set 100 screws 15 to said axle portions. The usual line spacing devices co-operate with the ratchet wheel. A set of type bars are provided that are adapted to co-operate with the front face of the platen 10, one of these 105 type bars 16 being shown in striking or printing position in Fig. 1, from which it will be observed that when at the printing point the type bar co-operates with a stationary abutment or anvil 17.

The carriage parts or end bars 9 are adjustably connected with the carriage part or cross bar 8 in such a way that their set relationship may be altered. In other words, 5 the end bars 9 may be raised or lowered to slightly raise or lower the platen thus bringing the printing face thereof in proper vertical position in parallelism with the guide bars or rails 4 and 6, and so that the platen 10 may be correctly adjusted on its supporting frame or carriage properly to receive the imprints of the types, vertically considered. To this end each end bar 9 is formed at its rear with an inwardly projecting portion or 15 footing 9^a which extends at right angles to the body of the end bar and is formed along its lower rearward face with a slightly projecting rib, strip or contact device 18. The rear face of this rib or strip 18 is machined 20 or finished in order to co-operate or engage closely with the lower portion of the front face of a boss or projecting portion 19 formed at the front of the carriage bar 8 and which is correspondingly machined. As 25 will be clear from Fig. 3, there is one of these bosses at each end of the rear bar 8, the bosses being rectangular in shape; and in between them the rear bar is preferably cut out, as indicated at 8^a, for the sake of 30 lightness. The end bars 9 are secured to the rear bar or cross bar 8 each by a headed screw 20 which passes forward freely through a hole 21 in the rear bar and is threaded into a tapped hole in the associate 35 footing 9^a, the head of the screw 20 being housed in a counter-sink or enlargement 22 of the rear part of the hole 21. The screw or tying device 20 is disposed about at the middle of the footing or extension 9^a passing 40 through said footing at about midway of its length from top to bottom as well as of its width, as will be understood from a consideration of Figs. 1 and 5. Arranged between the footing 18 and the boss or projection 19 is a key or short plate 23 which is housed in oppositely facing slotways in the boss and footing and is formed with a hole for the passage of the tie or binding screw 20. The construction is such that 45 when the screw 20 is tightened it binds or clamps the end bar to the rear bar, the key 23 preventing accidental slidable displacement in a vertical direction between the end bar and the rear bar. Directly above 50 each screw 20, a smaller headed screw 24 is threaded through the rear bar, the head of said screw being received in a depression or counter-sink 25 in said bar and its point projecting forward and being adapted to co-operate with the upper portion of the rear face of the footing 9^a. It will be observed, more especially from 55 Figs. 1 and 2, that a space or opening indicated at 18^a lies between the opposing faces of the footing and the rear bar, this 60 space corresponding substantially to the width or thickness of the strip or rib 18. The construction in effect provides a triangular or three-point bearing or contact between each footing 9^a and the rear bar, the contact being provided by the strip or contact device 18, extending substantially throughout the width of the footing at its lower side, and by the screw 24 which provides an 65 adjustable contact between the bar 8 and the upper end portion of the footing at about midway of its width. By first loosening the binding screws 20 and then screwing the contact screws 24 in or out to the desired extent, the platen will be correspondingly 70 lowered or raised when thereafter the binding screws are tightened, this result of course being due to the new adjustment of the contact faces of the screws 24. In effect, the end bars and the platen are swung or 75 moved slightly down or up, pivoting on the rear bar at the contact between the strip 18 and said rear bar, the printing face of the platen being slightly raised or lowered to the desired extent as a result. It will be 80 apparent that the carrier parts or end bars are independently adjustable thereby enabling adjustments at the opposite end portions of the platen to be separately effected. Means are also provided for adjusting the 85 printing face of the platen in fore-and-aft direction, such adjustment being more particularly effected for the purpose of bringing the printing face into correct relationship with the type bar anvil 17. Said fore-and-aft adjusting means comprises two 90 flanged sleeves 26 and 27 arranged at opposite ends of the platen, the sleeve 26 being received in an elongated opening indicated 95 at 28 in the left-hand end bar 9, and the 100 sleeve 27 being received in a similar opening 30 in the right-hand end bar 9. The flange 31 of the left-hand sleeve 26 is oval in shape, and is disposed outside of and contiguous to the outer face of the left-hand end bar 105 while the circular flange 32 of the sleeve 27 is correspondingly arranged outside the right-hand end bar 9. The sleeves are bored out to fit over the axle portions 12, the left-hand sleeve being counterbored as indicated 110 at 33 so that the bearing portion 34 of said sleeve is quite narrow, thus facilitating alignment and reducing friction. Similarly, the sleeve 27 is counterbored as indicated at 115 35 providing a comparatively narrow bearing surface 36. Oval washers 37 are arranged outside of and in contact with the respective sleeves 26 and 27. The right-hand washer is adjacent to the inner end of the hub 14 of the right-hand finger wheel 13, while interposed between the left-hand washer 37 and the associate hub 14, is a spacing sleeve 20. Pivot screws 39 threaded 120 into the lower portions of the end bars 9 pivotally support the sleeves 26 and 27 and se- 125 95 130

cure the lower end portions of the associate washers, said screws being provided with heads which when the screws are tightened serve to clamp the sleeves and washers to the 5 end bars. The upper end portion of the sleeves 26 and 27 are formed respectively with elongated slots 40 and 41 which are centered on the screws 39. These slots receive headed binding or clamping screws 42 10 which pass through round holes in the associate washers 37. On the other hand, the washers are formed with slots or elongated holes 43 to afford free passage therethrough and side play of the shaft portions 12. The 15 purpose of the washers is merely to prevent the adjusting sleeves from moving accidentally after they have been adjusted and before the screws 39 and 42 have been tightened sufficiently to hold them, the washers 20 themselves not being adjustable. The construction is such that when the set screws 39 and 42 are loosened, the bearing sleeves 26 and 27 may be swung either backward or forward slightly to the limit of the slots 40 25 and 41 about the screws 39 as centers, the elongated holes 28 and 30 in the end bars 9 affording sufficient play of the sleeves for this purpose. This movement of the sleeves correspondingly moves the platen which is 30 supported by them, the printing face of the platen either being advanced or drawn backward until it has been brought into correct relationship with the contact face of the anvil 17. After adjustment, the screws 39 35 and 42 are tightened, fixing the platen bearings or sleeves 26, 27 on the platen frame or carriage comprising the end bars 9, and thus confining the platen to a fixed path of rotation due to its axle or shaft portions 12 40 rotating in the bearing portions 34 and 36 at the left-hand and right-hand ends of the carriage.

Co-operative with the right-hand sleeve 27 at its inner ends is a platen end-thrust bearing of ordinary construction comprising a ball-race collar 44 which abuts against the outer end of the hub 45 of the right-hand platen head 46. End thrust balls 47 bear on the collar 44 and on the associate sleeve 50 27, said balls being controlled by a separator 48 and housed within a thimble-like retainer 49. The function and operation of the platen adjusting devices will be clearly understood from a comparison of Fig. 1 and Fig. 55 4, Fig. 4 showing the sleeve 26 readjusted from the Fig. 1 position to the extreme forward position resulting in a corresponding readjustment of the platen at its left-hand end portion. The right-hand adjustment is 60 of course similar. It will be apparent that there may be variations in the adjustments at the opposite ends of the platen, the sleeves 26 and 27 being, within limited extents, settable independently of each other.

65 By my present invention there is provided

simple and convenient means for effecting a universal adjustment, or adjustment in any desired direction, of the printing face of the platen on its support and relatively to the carriage track-ways and the type bar anvil. 70 The adjustments are all made preliminary to using the machine and said adjustments are not affected by the insertion of paper, being independent of the work sheets whatever their number or thickness. Moreover, 75 such adjustments may be made to any desired extent, not being limited to definite or prescribed distances or extents.

Various changes may be made without departing from my invention. 80

What I claim as new and desire to secure by Letters Patent is:—

1. In a typewriting machine, the combination of a platen, a platen carriage comprising a rear bar and a pair of end bars 85 having a set normal relationship, and means for affording a swinging movement of said end bars relative to said rear bar to vary their normal relationship and alter the normal position of the platen in a vertical direction. 90

2. In a typewriting machine, the combination of stationary guide-ways, a bearing part slidably supported on said guide-ways, platen supporting parts carried by said bearing part, a platen on said supporting parts, means for securing said supporting parts in fixed relationship with said bearing part, and means for affording variation in said fixed relationship to any desired extent. 100

3. In a typewriting machine, the combination of a platen, a platen carriage comprising a plurality of parts, and means for affording relative adjustment of the parts to vary the normal position of the printing face of the platen, said means comprising tying devices and also adjustable contact screws against which certain of said parts are adapted to be held by said tying devices. 105

4. In a typewriting machine, the combination of a platen, a platen carriage comprising a rear bar and end bars projecting forward from said rear bar and supporting the platen, adjustable means carried by said rear bar against which said end bars are adapted to abut, and screws for securing said end bars against said means in fixed relationship to said rear bar. 110

5. In a typewriting machine, the combination of carriage guide rails, a platen, a carriage for said platen comprising a cross bar co-operative with said guide rails, and end bars secured to said cross bar, said end bars comprising footings formed with contact faces, abutting screws carried by said cross bar and against which said footings are adapted to bear, and means for securing said end bars to said cross bar. 120

6. In a typewriting machine, the combination of stationary upper and lower guide 125

- 4
- rails, a platen, a platen carriage comprising a slide bar and end bars, roller bearings co-operating with said slide bar and with said guide rails, connecting means comprising 5 triangular contact devices between said end bars and said slide bar, said means affording an adjustment of at least one point of each triangular contact, and means for detachably securing said end bars to said 10 slide bar.
7. In a typewriting machine, the combination of a platen, a platen carriage comprising a plurality of parts, and sets of independent means co-operative with the ends 15 of said carriage for affording relative adjustment of the carriage parts at each end separately so as to vary the normal positions of the corresponding end portions of the platen.
8. In a typewriting machine, the combination of a platen, a platen carriage comprising a plurality of parts, and means co-operative with each end of said carriage for affording independent relative adjustment 20 of the parts at each end so as to vary the normal adjustment of the corresponding end portions of the platen in an up and down direction.
9. In a typewriting machine, the combination of a platen, a platen carriage comprising a cross bar and end bars, triangular contact devices between said end bars and said cross bar, means for affording an adjustment of at least one point of each triangular contact and for securing said end 25 bars to said cross bar, keys inserted between
- said cross bar and said end bars to prevent downward relative displacement between said end bars and said cross bar.
10. In a typewriting machine, the combination of a platen, a platen carriage, and bearings for said platen at opposite ends of said carriage, said bearings being independently adjustable to afford adjustments of the platen in a fore-and-aft direction. 40
11. In a typewriting machine, the combination of a platen, a carriage comprising end bars, bearing sleeves in said end bars for said platen, pivots supported on said end bars, and means for affording swinging 45 movements of said sleeves on said pivots and for clamping said sleeves to said end bars.
12. In a typewriting machine, the combination of a platen, a carriage comprising end bars, bearing sleeves on said end bars for said platen, means for affording swinging 50 movements of said sleeves and for clamping said sleeves to said end bars, and washer plates interposed between said sleeves and said means.
13. In a typewriting machine, the combination of a platen, axle portions projecting therefrom, a carriage comprising end bars, bearing sleeves on said end bars for said axle 55 portions, pivots for said sleeves, screws for adjustingly clamping said sleeves, and non-adjustable washer plates clamped also by said screws.
- Signed at Syracuse, in the county of Onondaga and State of New York this 4th 60 day of Sept. A. D. 1923.
- JOSEPH B. HOLDEN.
